CLAIM

The ornamental design for a bottle boot, as shown and described.

DESCRIPTION

FIG. 1 is a top perspective view of a bottle boot showing our new design;

FIG. 2 is a bottom perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines in the figures illustrate portions of the bottle boot that form no part of the claimed design.

1 Claim, 6 Drawing Sheets
